UNITED STATES PATENT OFFICE.

MAX MAAG, OF SCHWAMENDINGEN, NEAR ZURICH, SWITZERLAND.

PRODUCTION OF SOUNDS.

Application filed December 30, 1922, Serial No. 610,076, and in Germany December 31, 1921.

My invention relates to a new device or means for producing sounds with the aid of what may be termed sounding curves.

It is known that by blowing towards and upon a moving disk, ring or band, having its edge or edges shaped to conform to a sounding curve, sound can be produced corresponding to the particular shape of the said sounding curve (wave siren).

10 The object of my invention is to provide a sound producer constructed in accordance with the above indicated idea or principle. To this end my invention provides means for producing sounds in a sounding tube, preferably of funnel-shape, into which air is blown or sucked and which at one of its ends terminates in a mouth or opening located in front of the sounding curve carrier (band, wheel, or the like), while its 15 other end opens freely into the atmosphere. Through the latter end of the sounding tube, therefore, a portion of the blowing air is allowed to flow out, the amount of said portion depending upon and corresponding to the degree to which the aforesaid mouth of the tube is closed or covered by the sounding curve band or wheel, that is to say the more the said band or wheel acts to close or occlude the mouth or passage, the more 20 air is caused to take its way out through that end of the tube which immediately opens into the atmosphere. The portion of the blown or sucked in air thus escaping directly into the atmosphere and forming what 25 may be termed the "reaction-air", is adapted to produce in the sounding tube air pushes or pulsations which result in the production of sounds. Herein resides the essential feature of my invention.

40 As an advantage thereof the sounding body, wheel or band, can be moved in front of and over the blowing mouth of the tube in closest proximity thereof so as to practically close the same at intervals. This is 45 so the blowing air is free to escape even in case of a complete closure at the mouth from the opening at the other end of the tube and thus any disturbing reaction in the blowing device resulting in variations of pressure and sound cannot be produced. Consequently a relatively moderate expenditure of air is ensured and still a very perfect and exact reproduction of the single sounds of the sounding curve coacting to compose 50 the tonality acoustic character or timbre, is

obtained, mainly owing to the strict limitation of the current or flow of air forced through the mouth of the tube located in close proximity to the curve-rimmed sounding band or wheel.

60 In the accompanying drawing I have shown several embodiments of my invention. In the drawing Figure 1 is a side elevation of the sounding device or apparatus, partly in section, Figure 2 is a plan thereof with 65 certain parts broken off. Figures 3 and 4 are two different views of a portion thereof, Figures 5 to 7 are sectional views illustrating certain details of modified construction, Figures 8 and 9 are perspective views of 70 modifications of the principal parts of the device, and Figures 10 to 14 are another modification, shown in several sections and views.

75 Referring to Figs. 1 and 2 a roll 1 driven by any suitable means (not shown) to rotate at a uniform speed, carries a ribbon or band 2 adapted to unwind from a roll 3 and to be wound upon a roll 4. The band 2 is provided with or shaped to form undulatory or dentiform projections or laps at one of its longitudinal edges, as in Fig. 3, or at both edges, as in Fig. 2. In the latter case the said projections or laps are shaped and located symmetrically with regard to the longitudinal median line of the band. These projections and the gaps or recesses therebetween represent in either case 85 complements of the sounding curve to be reproduced.

90 Diametrically opposite the roll 1 a sounding tube 5 is mounted with its mouth 6 in close proximity of the band 2. The mouth 6 of the tube is slot-shaped or enlarged, as will be clearly seen in Figs. 2 and 3, to extend over the whole width of the band. The other end of the tube 5 is preferably funnel-shaped and arranged to extend into the open air. Adjacent to the slot-shaped mouth 6 an air supply pipe 8 is provided opening 95 into the tube 5 a little above the edge of the mouth and having a gradually increasing or flaring shape where it approaches the tube 5 to conform to the shape of the mouth 6, as will be clearly understood on inspection of Fig. 2. The pipe 8 is provided with a mechanically or manually controllable valve 9 and has an extension 10 connected with a blower 11 of any convenient type.

100 Assuming the valve 9 is open and air is 110

forced into the tube 5, the forced in air will take its way, as indicated by the two arrows in Fig. 1, in two directions, that is to say, towards the two ends of the tube 5. 5 Further assuming the band 2 is caused to move with a uniform speed over the periphery of the roll 1, now when a wider or lapped portion of the band passes below the mouth 6, the latter will be closed by 10 the band more or less and a correspondingly increased or reduced amount of the air injected by the pipe 8 will take its way towards the free end of the tube 5 opening into the atmosphere. In the two limit 15 cases, that is where the lapped band 2 covers and closes the mouth 6 to its full width and where the width of the band is practically equal to zero, as shown in Fig. 3, the whole volume of air injected at that 20 moment into the tube 5 will, in the former case, be forced out therefrom through the funnel-shaped free end of the tube, whereas, in the latter case, about one half of the injected air will flow towards the funnel-shaped end of the tube 5, while the other 25 half thereof will pass through the mouth 6.

If, therefore, the band 2 is shaped and lapped in a manner that portions of largest width follow each other in succession with 30 narrow sized portions intermediate between each two lapped portions, more or less air will be forced, in corresponding alternation, towards and through the funnel-shaped end of the tube 5, and a pulsatory air current 35 will be produced therein. Obviously the pulsations of such a current occur and are in strict accordance or time with the laps of the band 2 passing the mouth 6, said pulsations acting to alternately produce in the 40 sounding tube 5 heavier and lighter compressions of the air therein, which will issue from the funnel-shaped end 7 as audible sounds of different timbre, provided that the frequency of the pulsations is within the 45 vibratory range of audible sounds.

The expenditure of pressure air may be reduced and still the efficiency will be increased by producing very vigorous pulsations in the sounding tube. For this purpose the device or apparatus may be constructed and arranged in a manner that the air current passing from the supply pipe 8 over into the sounding tube 5 will be adapted to produce not only more or less considerable compressions of the air in the tube, 55 but also rarefactions or vacua therein.

A construction of the kind is shown in Fig. 5, wherein the supply pipe 8 is attached to the tube 5 at an acute angle, so 60 that the current of air forced in by the former acts in the manner of an ejector to push the air contained in the tube 5 out towards and through the mouth 6. Consequently if the mouth 6 is free and not closed or covered, no air will flow towards the

funnel-shaped end of the tube 5, on the contrary, the air contained therein will be sucked out and rarified and a current of air will flow therefrom towards and through the mouth 6. If, however, the mouth 6 is 70 covered or closed, the current of air forced in by the pipe 8 will, without any division, in its totality escape through the funnel-shaped end 7 of the tube 5. Hence the alternation in partly or totally closing and 75 opening the mouth 6, therefore, will result in producing more powerful pulsations in a construction, as shown in Fig. 5, and more vigorous sounds will be obtained than by the construction illustrated in Fig. 1. 80

In the embodiment of my invention shown in Figs. 6 and 7 the air supply pipe 8 is located within the sounding tube 5 and its downwardly extending end 12 is flattened out to form a flaring slot a little 85 above and in conformity with the mouth 6 of the tube 5. By this construction the air is sucked out from the tube 5 in a very powerful manner, when the mouth 6 is uncovered. Also in this modification all the air 90 coming from the supply pipe 8 will be driven towards and through the free upper end of the sounding tube, when the mouth 6 is covered or closed. A particular advantage of the construction shown in Figs. 6 95 and 7 resides in the fact that by properly adjusting the vertical position of the air supply pipe 8 with relation to the tube 5 or mouth 6 the sucking efficiency can be controlled and regulated. 100

The device described in the foregoing, especially the apparatus as shown in Fig. 1 containing the sounding curve on a band of corresponding length is primarily adapted to reproduce musical and talking pieces 105 of greater length, in particular for a wide range and variety of successive sounds. But my invention is likewise capable of reproducing tunes of an invariable number of oscillations and invariable sounding character, therefore for tones adapted for the construction of organ-like instruments. In this case the sounding curves are preferably arranged as cylindrical rings, as shown in 110 Figs. 8 and 9.

A ring of this kind comprises a shaft 13 with radial arms or spokes and a rim 14, the whole forming a kind of a wheel. In the construction shown in Fig. 8 the rim is shaped by cutting, punching, etching or 115 in any other suitable manner to form two lapped rings with the laps or teeth opposed to each other, so that the gap therebetween has a form and contour similar to that of the band 2 shown in Fig. 2 and representing 120 what may be termed the "sounding curve." In the modification illustrated in Fig. 9, however, the ring itself is shaped at its edges to form the sounding curve and similar to 125 the band 2 in Fig. 2, as regards its contour. 130

In both embodiments, Figs. 8 and 9, the sounding curve is moved by the rotation of the shaft 13, to pass below the mouth of the sounding tube 5 and, in doing so, caused to 5 throttle the air current emanating from said mouth, more or less in accordance with the shape of the point of the curve just below the mouth, whereby the sound producing pulsations or pushes of the air are brought 10 about.

Further, the sounding curves may be formed at the edge of discs rotating about their axles like a wave siren, an air stream being blown against the toothed edge. Instead of the sounding curves being formed 15 as described above holes of a proper shape may be punched into a disc or a ring, the holes being arranged on a circle concentric to the rotating axle. The blowing mouth 20 in a device of such kind is not made of a rectangular cross section but in the same shape as the holes. Attending to the theoretical requirements it is possible to get in 25 all these cases air thrusts of a suitable sounding character.

To get strong tones waving for instance in net sine form the arrangement may be performed in such manner that the reaction impulse brought about in the suction chamber of the blowing pipe, instead of being directed upon a sounding body, is led by a pipe into a resonator, the oscillation proper is brought in conformity with the frequency of the reaction impulses.

Such device is shown in Figs. 10 to 14, Fig. 10 showing a cross-section through the sounding curve carrier being shaped like a siren disc, the blowing mouth and the resonator, Fig. 11 showing a side-view and Fig. 40 12 an elevation, partly in section. Fig. 13 shows the blowing mouth in a larger scale, and Fig. 14 a simplified modification.

Referring to Figs. 10 to 13 a disc 15 fixed to a shaft 15' has concentrical positioned 45 holes 16 of a triangular shape and is rotated with uniform velocity. The extension of the holes on the concentric circle in which they are arranged is equal to the distance of two adjacent holes. The radial extension is of no importance. A blowing mouth 17 is vertically directed against the disc and opposite to the circle of the holes 16, the said blowing mouth consisting in a box 18 containing a blowing pipe 19 connected 50 by a pipe 20 to a blower (not shown). In the pipe 19 is fixed by stems 23, 23 a needle 21 of such shape that the air stream escaping from the pipe 19 is divided and pressed outwardly against the mouth of a suction-pipe 24 into the suction chamber 22, in order 55 to increase the suction effect. The mouth of the box 18 has the same shape as the holes 16. This shape is so that on the disc 15 being rotated air thrusts are brought 60 about in the reaction chamber 22, the

strength of which begins with a maximum on the mouth 17 being closed by the disc, then becomes weaker in sinus form on the said mouth being more and more set free by a hole 16, going through nought to a minimum, which is reached when the mouth is fully set free, and then increases again when the mouth being more and more closed by the rotating disc, through nought to maximum, always following the sine curve. 75

The reaction chamber 22 is connected by a pipe 24 to a resonator 25, the oscillation proper of which is tuned to the frequency of the air thrusts of the reaction impulse, the said frequency being equal to the product 80 of the number of the holes 16 with the number of rotations per second of the disc 15.

Preferably the air stream on the back side of the disc is not allowed to blow out in the free air but is caught by mouth piece 26 and led by a pipe 27 into the resonator 25. Thereby the said impulse is free from all disturbing noises and arrives at the resonator as an impulse of pure sine form, increasing the reaction impulse. To secure this result it is necessary that the lengths of the two leading pipes 24 and 27 differ from each other by an odd number of half a wave length of the tone to be produced. 90

This is due to the fact that the two impulses, the reaction impulse and the siren impulse oscillate in opposite phase, so that an air compression takes place in the mouthpiece 26 while there is a rarefaction in the reaction space 22 and vice versa. Therefore the two impulses lead into the resonator by leading tubes of equal length would arrive there in opposite phase, the effect of which would not be a reinforcement of the oscillation but a 100 weakening of it. In order to get the desired reinforcement it will be necessary that the two impulses arrive in the resonator in equal phase. This may be reached by a difference in length of the two leading pipes 110 equal to one-half wave length of the tone to be produced or of any odd multiple of it, as two adjacent nodes of any oscillation are in opposite phase and at a distance of half a wave length. 115

It is of no importance whatever, which of the leading pipes be the longer one. Also it is of little importance how long the one is made. A certain profit in loudness may be gained, however, if the length of the one leading pipe is made equal to half a wave length of the tone to be produced or an odd multiple of it, as in this case a standing wave is produced which results in a reinforcement of the impulse. 120 125

The two pipes 24 and 27 may, instead of being introduced individually into the resonator, be combined with each other in the following way: the siren impulse may be led by a pipe of the length of one-half wave 130

length or an odd multiple of it of the tune to be produced into the reaction chamber and therefrom, together with the reaction impulse, by a common pipe to the said resonator. Such device is shown in Fig. 14, in which 28 is the described pipe leading the siren impulse to the reaction chamber 22, and 29 the pipe common to both impulses and leading then to the resonator 25. The 10 length of the pipe 28 must be, as explained, equal to one-half of a wave length, or equal to an odd multiple of one-half wave length, the length of the pipe 29 being of little importance as explained above.

15 Obviously the reaction impulse could be led from the chamber 22 into the mouth 26 and therefrom, together with the siren impulse, into the resonator 25.

It is obvious that in lieu of a blower, such 20 as 11, sucking devices of appropriate kind may be employed in connection with the described new apparatus, since by sucking off the air from the sounding tube 5 through the pipe 8 more or less powerful pulsations or 25 rushes of air are produced, by the agency of the mouth 6 or 12, respectively, and such pulsations, likewise, escape from the sounding tube in the form of sounding waves of 30 different timbre and acoustic character in accordance with the degree of occlusion the mouth 6 or 12, respectively, has to undergo just as in case of using a blower.

I have not attempted to explain all of the 35 minute details of the construction of a sounding device made according to my invention, for it will be understood by those, to whom this specification is addressed, that the parts required in such construction will be of the proper size and relationship, and 40 will be properly mounted and supported in accordance with the tenets of machine construction; nor have I attempted to illustrate the parts in their exact sizes and dimensions as many of the parts are conventionally 45 shown.

While I have diagrammatically shown and described a few specific constructions it is obvious that the devices shown can be modified without departing from the spirit 50 and scope of my invention.

What I claim as my invention is:—

1. A sound producing device comprising a sounding tube having a sounding end freely open to the air and a sound producing end, 55 means co-operating with the said sound producing end to close the same more or less, an air pipe connected with the said tube to open thereinto adjacent to the sound producing end, a device in connection with said air pipe and adapted to force therethrough a current of air toward the pulsations producing end, means permitting said current to escape simultaneously through said tone producing and pulsation producing end, and means for controlling the op- 60

eration of the said device, essentially as and for the purpose set forth.

2. A sound producing device comprising a sounding tube having a sounding end freely open to the air and an air pulsations producing end, a figurate band movable to co-operate with the latter to close the same more or less, an air pipe connected with the said tube and opening thereinto adjacent to the said narrower end thereof, a device in connection with said air pipe and adapted to cause a current of air to move therethrough toward the pulsations producing end, means permitting said current to escape simultaneously through said tone producing and pulsation producing end, and means for controlling the operations of the said device, essentially as and for the purpose set forth. 70 75 80

3. A sound producing device comprising a sounding tube having a sounding end and a slot-shaped air pulsations producing end, a figurate band movable to co-operate with the latter to close the same more or less, an air pipe connected with the said tube and having a slot-shaped end opening thereinto adjacent to the aforesaid slot-shaped end thereof, a device in connection with said air pipe and adapted to cause a current of air to move therethrough toward the pulsations producing end, means permitting said current to escape simultaneously through said tone producing and pulsation producing end, and means for controlling the operation of the said device, essentially as and for the purpose set forth. 85 90 95 100

4. A sound producing device comprising a sounding tube having a wider sounding end and a narrower air pulsations producing end, means co-operating with the last stated tube end to close the same more or less, an air pipe attached to the said tube at an acute angle adjacent to the narrower end thereof, a device in connection with said air pipe and adapted to force therethrough a current of air, and means for controlling the operation of the said device toward the pulsations producing end, means permitting said current to escape simultaneously through said tone producing and pulsation producing end, essentially as and for the purpose set forth. 105 110 115

5. A sound producing device comprising a sounding tube having a sounding end and an air pulsations producing end, a figurate band movable to co-operate with the latter to close the same more or less, an air pipe attached to the said tube at an acute angle adjacent to the narrower end thereof, a device in connection with said air pipe and adapted to cause a current of air to move therethrough toward the pulsations producing end, means permitting said current to escape simultaneously through said tone producing and pulsation producing end, and 120 125 130

means for controlling the operation of the said device, essentially as and for the purpose set forth.

6. A sound producing device comprising in combination a sounding tube having a sounding end and a slot-shaped air pulsations producing mouth, a figurate band movable to co-operate with the latter to close the same more or less, an air pipe adjustably inserted in the said tube with its inner end in co-axial relationship thereto and with its flaring slot-shaped mouth in alignment with the slot-shaped mouth of the sounding

tube, a device in connection with said air pipe and adapted to cause a current of air to move therethrough toward the pulsations producing end, means permitting said current to escape simultaneously through said tone producing and pulsation producing end, and means for controlling the operation of the said device, essentially as and for the purpose set forth.

In witness whereof I have hereunto signed my name this 7th day of December, 1922.

MAX MAAG.
